UNITED STATES PATENT OFFICE.

JOHN LEE RORISON, OF BAKERSVILLE, NORTH CAROLINA.

COMPOSITE MICA SHEET.

SPECIFICATION forming part of Letters Patent No. 308,199, dated November 18, 1884.

Application filed January 5, 1884. (No model.)

To all whom it may concern:

Be it known that I, JOHN L. RORISON, of Bakersville, county of Mitchell, North Carolina, have invented a new and improved 5 Composite Mica Sheet for Stoves, &c., of which the following is a full, clear, and exact description.

My invention consists in the employment of several small pieces or sheets of mica for making large sheets—sheets of sufficient size to be used in illuminated stoves and in other places—as hereinafter set forth in the claims.

Reference is to be had to the accompanying drawings, forming part of this specification, 15 in which similar letters of reference indicate corresponding parts in all the figures.

Figure 1 is a front elevation of a large sheet of mica made up of four small pieces or sheets. Fig. 2 shows the method of preparing the 20 edges of the small pieces of mica to be united when two small pieces of mica are used; and Fig. 3 is a sectional elevation taken on the line $x-x$ of Fig. 1, showing the preferred method of securing the small sheets or pieces 25 of mica at their contiguous edges or corners.

A represents the completed sheet of mica. This is composed of the four small pieces or sheets b of mica, which are held together at 30 their contiguous corners by the rivet c and washer d . In uniting these four pieces of mica the inner corner of each sheet is slightly cut away, so that when they are put together a central opening will be formed for the passage of the rivet c . The two inner edges of 35 each small sheet b are notched or slotted, as shown at e , near their outer ends or edges, and when the pieces are put together the opposite edges to those in which the slots are made are placed in the slots e , as shown in 40 Fig. 1, so that the edges lap past each other, forming good joints, and are at the same time locked together. The contiguous edges of the small pieces b being properly placed together, the rivet c is then inserted, and then 45 the washer d is placed upon the smaller end

of the rivet and the rivet headed down, so as to cause the head c' of the rivet and the outer edges of the washer to grasp and firmly hold the small pieces b of mica, as will be understood from Fig. 3, thus making the sheet 50 A as firm and strong and durable as though it were one continuous sheet of mica. When only two small pieces or sheets b of mica are used for making the large sheet, the two contiguous edges of the pieces will be slotted, as 55 shown at e , in Fig. 2, to form the lap and lock-joint, and in the center the two contiguous edges will be cut away, as shown at f , to form a passage for the rivet c , so that by heading the rivet upon the washer d the two sheets 60 will be held firmly together.

I am aware that a stove-pipe has been formed of a sheet-metal plate having alternate projections and recesses on its longitudinal edges, said projections being bent at their junction 65 with the body of the pipe. These projections overlapped adjacent portions of the body; but the body portions themselves did not overlap at any point, and I do not claim any such construction.

Having thus described my invention, I claim 70 as new and desire to secure by Letters Patent—

1. The sheet A of mica, composed of the small sheets b , slotted on their adjacent edges at opposite ends, as shown at e , to allow the 75 entire edges to overlap and lock, and a rivet and washer for securing said adjacent edges together, substantially as shown.

2. The sheet of mica A , composed of small sheets b , slotted on their adjacent edges at opposite ends and notched at $f-f'$, to allow of a 80 central aperture being formed when the edges are overlapped and interlocked, and a rivet, c , passing through said aperture and secured by washer d , substantially as set forth.

JOHN LEE RORISON.
